UNITED STATES PATENT OFFICE

ARTHUR LINDSAY THOMSON, OF MILAN, ITALY, ASSIGNOR TO ALTEK COMPAGNIE D'ETUDE ET D'EXPLOITATION D'APPAREILS FRIGORIFIQUES POUR LE TRANSPORT, OF ANTWERP, BELGIUM, A BELGIAN COMPANY

APPARATUS FOR THE VENTILATION OF COOLING PLANTS

Application filed March 15, 1929, Serial No. 347,259, and in Belgium November 3, 1928.

My invention has reference to cooling plants and it relates in particular to movable plants or units for the transportation of perishable goods. The object of this invention is to provide an efficient method and means for regulating the ventilation of the cold storage room or chamber and the humidification of the atmosphere in said room, so that the conditions most favourable to the preservation of any desired kind of goods can always be obtained and maintained.

It is well known that the preservation of perishable food depends not only on the surrounding temperature but also on the composition of the atmosphere and in particular on its degree of moisture which has to be varied according to the nature of the goods to be preserved. It is necessary therefore that the cold storage chambers be ventilated with moist air and it has already been proposed to circulate air introduced into said chambers in contact with water or with ice in order to cause it to absorb a certain degree of moisture. This method, however, does not permit of an accurate regulation and it is not suitable for transportable plants where the presence of water in large amounts always gives rise to difficulties.

In my co-pending patent application Ser. No. 347,258 of even date, I have described a method of ventilating cold storage rooms and preserving at all times a suitable degree of moisture in such air, while avoiding the inconveniences stated above, which consists in passing the air, on its way to the storage room, over ice in contact with the pipes, coils or the like, through which circulates the cooling medium used for refrigerating said room.

I have found that in some cases the natural humidity of the atmosphere can be relied upon to supply the ice necessary for moistening the ventilation air, and in accordance with my present invention I cause this air to flow in a confined space in contact with the refrigerating pipes themselves, before it is admitted into the storage room. The atmospheric moisture condensing on

and this ice melting superficially under the action of the comparatively warm air supplies more or less moisture according to the temperature and the rate of flow of the incoming air.

When cold accumulators are used, such as brine tanks cooled by the refrigerating pipes, the air may be sent over these tanks instead of directly over the refrigerating pipes themselves. In this case, however, it is advisable to circulate the air both over the exposed portions of the refrigerating pipes and over the cold accumulators, as on the latter the formation of an external coating of ice only takes place when their temperature has become sufficiently low.

According to an embodiment of my invention which is of particular advantage for use in railway cars, the fan sucks air from the cold storage room through a central conduit extending longitudinally of said room, at the top thereof, while the air driven by the fan is directed through parallel side conduits over the refrigerating pipes and/or over the cold accumulators located on either side of the suction conduit.

The air inlet and outlet openings in the cold storage room are preferably staggered to avoid any short circuit, the arrangement being such that the air cooled by its contact with the refrigerating pipes will sink into the storage room while the air heated by its contact with the stored goods rises towards the central conduit. The same air can be used over and over again and circulate, for some time at least, in a closed circuit, and air purifying means then may be interposed in or branched on the circuit.

In the accompanying drawing I have diagrammatically illustrated, by way of example, an apparatus of this kind applied to a refrigerator car.

Fig. 1 is a vertical longitudinal section on line I—I of Fig. 3.

Fig. 2 is a horizontal section on the broken line II—II of Fig. 3.

Figs. 3 and 4 are cross sections respectively on lines III—III and IV—IV of Fig. 1.

In the drawing 1 is the cold storage room which extends over nearly the whole length

of the car and has heat insulated walls 2 and roof 3. At the top of this room are the refrigerating pipes 4 through which circulates a liquid having a low boiling point, such as liquid ammonia, supplied by suitable refrigerating apparatus (not shown). As shown, the pipes 4 extend through brine tanks 5 acting as cold accumulators.

The pipes 4 and brine tanks 5 are located under the roof 3 in longitudinal compartments 6 formed between a central longitudinal passage or conduit 7 and two side conduits 8. The conduit 7 is connected with the suction side 9 of a fan 10 which, in the example illustrated, is driven by an electric motor 11 and mounted in a heat insulated chamber 12 located at one end of the car. The fan 10 drives the air through the outlet 13 into the delivery passage 14 on which are branched the two conduits 8.

From the conduits 8, the air passes into the compartments 6 through side openings 15 and after having circulated in contact with the exposed surfaces of the pipes 4 and tanks 5, it enters the storage room 1 through openings 16 in the bottom of the compartments 6. The openings 16 may be provided with dampers or the like, herein shown in the form of louvres 17, in order to control the flow of air from the compartments 6 into the room 1.

In the bottom of the central conduit 7 are provided suction openings 18 which are preferably staggered with respect to the openings 16 so that the cold air issuing from the openings 16 will not be influenced by the suction through the openings 18. As shown, the openings 15, 16 and 18 may conveniently be distributed over substantially the whole length of the room 1.

When the refrigerating apparatus are operated, the pipes 4 quickly get covered with ice and likewise the tanks 5, when the temperature of the brine has been lowered sufficiently, such ice being formed at the expense of the moisture in the comparatively warm surrounding atmosphere. Air driven by the fan through the conduits 8 is cooled in the compartments 6 and absorbs more or less moisture from the melting water which forms on the surface of the ice. The cold air sinks through the openings 16, circulates in the storage room 1, and as it absorbs heat from the stored goods, it rises until it is sucked through the openings 18 into the conduit 7.

By varying the speed of delivery of the fan 10 and, if required, by adjusting the louvres 17, the ventilation of the storage room and the degree of moisture of the air can be regulated at will. Any excess melting water is collected in drip pans 19 suspended, under the pipes 4 and tanks 5, from cross bars 20 supporting the conduits 7 and 8. Additional means may be provided if desired in order to control the flow of air

through the openings 15 and 18, and changes made in the construction and arrangement of the apparatus described, without departing from the scope of the appended claims.

I claim:

1. In a cooling plant, the combination of a cold storage room, a compartment in said room, refrigerating pipes in said compartment, an air supply conduit adjacent said compartment, a series of passageways between said conduit and said compartment, a series of passageways between said compartment and said room, means for controlling the passageways of one of said series, and means for blowing air into said supply pipe at a controllable rate. 70

2. In a cooling plant, the combination with a cold storage room, of a compartment at the top of said room extending longitudinally thereof, refrigerating pipes in said compartment, an air conduit parallel to said compartment and connected therewith through openings, said compartment having bottom apertures opening into said room, and means for blowing air through said air 80 conduit. 85

3. In a cooling plant, the combination with a cold storage room, of a compartment at the top of said room extending longitudinally thereof, refrigerating pipes in said compartment, an air conduit adjacent and parallel with said compartment and connected therewith through side openings, said compartment having bottom apertures opening into said room, an electric fan, said conduit being connected to the pressure side of said fan, and another conduit connecting said room with the suction side of said fan. 90

4. In a cooling plant, the combination with a cold storage room, of a compartment at the top of said room, refrigerating pipes in said compartment, cold accumulators in said compartment in contact with said pipes, an air conduit adjacent said compartment, said compartment communicating both with said conduit and with said room, and means for sending a regulable current of air through said conduit and said compartment into said room. 100

5. In a cooling plant, the combination with a cold storage room, of an air suction conduit extending longitudinally of said room at the top thereof, air supply conduits extending parallel to said suction conduit on either side thereof and spaced apart 110 therefrom, refrigerating pipes in the spaces comprised between said supply conduits and said suction conduit, said supply conduits having openings facing said pipes, and an electric fan having its pressure and suction 115 sides respectively connected with said supply conduits and said suction conduit. 120

In testimony whereof I affix my signature.

ARTHUR LINDSAY THOMSON. 130
